DESIGN FOR A SKEIN HOLDER

Harry Reom, Jr., Oakland, Calif.

Application June 24, 1936, Serial No. 63,455

Term of patent 7 years

To all whom it may concern:

Be it known that I, Harry Reom, Jr., a citizen of the United States and a resident of Oakland, in the county of Alameda and State of California, have invented a new, original, and ornamental Design for a Skein Holder, of which the following is a specification, reference being had to the accompanying drawing, forming part thereof, wherein,

Figure 1 is a perspective view of a skein holder embodying the design of my invention and in condition for use.

I claim:

The ornamental design for a skein holder, substantially as shown.

HARRY REOM, JR.
